OIL FILLED HIGH VOLTAGE CABLE

Ernst Kirch, Berlin-Oberschoneweide, Germany,
assignor to General Electric Company, a corporation of New York

Application December 14, 1932, Serial No. 647,200
In Germany January 9, 1932

13 Claims. (Cl. 173—268)

Oil filled high voltage cables now in service are provided with feeding and compensating containers or reservoirs for the compensation of temperature-produced variations in the volume of the oil filling. The containers are located at suitable points on the line as in manholes, for example, and are in communication with the oil filled space of the cable through the medium of receptacles known as joint casings or boxes. It has been proposed to combine the oil-feeding container and the cable fittings in one unit, but known fittings of this kind have disadvantages which render their use impossible, either from a technical or an industrial point of view. In one construction, air is immediately above the oil in a domed chamber of the container and it is taken for granted that the oil within the cable is fully saturated with this gas. It is, however, common knowledge that the use of oil containing dissolved gases is detrimental, so that the actual practice is to use degasified oils only, that is to say oils which are freed to a high degree from their dissolved gas. Since, however, highly degasified oils are capable of absorbing a volume of gas approximately equal to that of the oil, the air contained in the chamber of the expansion vessel would be absorbed by this oil within a very short time so that the expected result is lost. Another known construction, provided with metal partitions acting as diaphragms avoids the disadvantage above noted but involves such large dimensions for a compensating chamber of a capacity of only a few litres that the construction is too costly and therefore uneconomical as compared with the arrangement of separate boxes and compensating containers. Moreover, reliability is imperilled by the circumstance that the sheet metal partitions are subjected to very high bending stresses as a result of the "breathing" effect of the cable.

The present invention has for its object to obviate these disadvantages and to provide an improved arrangement of an expansion vessel with a cable fitting wherein a non-metallic, resilient and/or collapsible oilproof partition is disposed between the impregnating agent of the cable and the pressure-compensating medium.

The partition is suitably made from a rubber-like oil insoluble and very elastic insulating agent comprising the products of polymerization of an acrylic acid or a product of polymerization of its derivative, or again a product of polymerization of homologues alone or in a mixture, if necessary with an additional material such as paper, mica, etc. Other synthetic and equivalent insulating

agents may also be used of which "vinapas" may be taken as an example. "Vinapas" is a material comprising polymerized vinyl compounds, particularly poly-vinyl compounds. When used alone, these materials may be formed into cylindrically or otherwise shaped elements by dipping, adhesion, compression, rolling or other processes; when used in combination with reinforcements, for example fabrics, the latter are impregnated and coated with the said materials and are thereby rendered impermeable. The materials above referred to are rubber-like in the sense that they are capable of stretching under the influence of applied pressure and are capable of self contracting when the pressure is removed. They are unlike rubber in that they are not affected by the oil contained in the cable.

With cables containing oil in their unoccupied spaces or on the surface of the cores, the expansion vessels are merely sleeve-shaped members which may be disposed at any point along the length of the cable and surrounding a suitable opening or openings in the lead sheath thereof. In cables in which the oil is within the cores, the expansion vessels may be combined with the known junction or joint boxes. The expansion vessels just described may be used not only on cables having very thin insulation oils but also with cables containing viscous impregnating materials, whether oils or compositions. Greater viscosity makes it necessary to use a large number of such vessels or to work them under higher pressure.

Constructional examples of the subject matter of the invention are illustrated in the accompanying drawing, in which Fig. 1 illustrates an expansion vessel surrounding the sheath of a cable; Fig. 2 illustrates a modified form of the vessel in longitudinal section taken on line 2—2 of Fig. 3; Fig. 3 is a sectional view taken on line 3—3 of Fig. 2; Fig. 4 illustrates a further modification of the expansion vessel; Fig. 5 illustrates the application of a vessel of the type shown in Fig. 1 to a joint; Fig. 6 illustrates a cable terminal, and Fig. 7 is a detail view illustrating one of the automatic valves for controlling the flow of oil through the sheath.

For a consideration of what I believe to be novel and my invention, attention is directed to the accompanying description and to the claims appended thereto.

Fig. 1 shows a sleeve-shaped expansion vessel which may be fitted at any point of the cable, whether of the multiple conductor type with oil channels in the outer unoccupied spaces, or of

the single conductor type with oil channels directly under the lead covering. Oil outlets or radial ports 7 are made in the lead sheath of the cable 8 and are screened for example by 5 a perforated metal sleeve 9 forming the inner limiting surface and a support for a nonmetallic resilient partition 10, said partition defining a compensating vessel. Instead of making the ports in the sheath itself they may be made in 10 a device generally similar to the connector shown in Fig. 5, and referred to later. Such a vessel may take the form of a tube applied over the sheath or the sheath may be interrupted to receive it. The initial position of the partition 10 is determined by the metal screen 9 which prevents the said partition from being damaged when air in the space between the cable and partition is exhausted through the connection nipple 10^a. The nipple may also be used if it be desired 15 to deliver degasified oil to the chamber within the vessel defined by the elastic partition 10. In Fig. 1, the partition is secured, for example, by wire ligatures 11 and 12, to the two ends of the metal screen 9 which at these points form 20 soldered fluid-tight joints with the lead covering of the cable. The partition may also be directly and hermetically secured to the cable sheath. This assembly is surrounded, at a certain distance, by an air-tight sleeve or casing 13 and 25 the space 14 between the latter and the resilient partition 10 forms an expansion chamber preferably filled with a neutral or easily dissolved gas under more or less high pressure. To permit introduction of such gas into the chamber, the 30 said sleeve is provided with a suitable fitting 13^a. The fitting also permits of access to the nipple 10^a.

The compensating vessels are more easily mounted in position when the oil ports 7 in the cable covering are closed as for example by 40 valves. Ball or conical valves 22, Fig. 7, may be used for this purpose and are so arranged that they are pressed upon their seats as long as the cable is under pressure, i. e., as long as it is closed to the outside. Any suitable means may 45 be employed to retain the valves in proximity to their respective seats. In this figure 8 may be taken as indicating the sheath of the cable or a split tube surrounding it and sealed thereto at its ends and along the joint. As illustrated here- 50 in the opening operation of the valves is carried out by making the pressure outside the valve equal to or higher than the internal pressure of the cable so that a suitable number of the closing balls or cone valves will drop by gravity and 55 allow the oil to flow out through the ports. The valves may of course be of other forms and be actuated in any desired manner. As will be evident, these valves are only used once and that while the installation is being made. After the 60 external pressure is applied to open them, they remain in said position and therefore exert no controlling effect on the insulating fluid in its passage between the cable and the exterior thereof.

65 Other constructional examples of the expansion vessel are illustrated in Figs. 2 and 4. The casing 13 of Fig. 2 encloses a compressible sack-shaped element 15 which appears in cross section as an annular hollow body and which is made of the hereinbefore mentioned material. The longitudinal division, Fig. 3, is provided to 70 simplify the assembly. The resilient tubular element 16 of Fig. 4 is coiled within the casing 13 and around the cable. In these cases, the resilient element contains the compressible me-

dium and both are made of the material referred to above which is not affected by the impregnating oil or compound.

It may be desirable to give to one or the other form of chamber of the expansion vessel a greater or lesser capacity, according to the cross section of the parts; this may be done without difficulty by connecting to the chamber an additional gas chamber 17 (Fig. 2). These chambers may be 10 formed in metal walled casings. 10

Fig. 5 shows a joint or casing used with hollow conductor cables and provided with an expansion vessel. The two ends 18 and 19 of the hollow conductor of the cable are conductively united by means of a tube 20 having end sockets 15 for the conductors and provided with axial slots or ports 1 in order that the oil may flow out of the said hollow conductor into the expansion chamber proper through the wound insulating means 21 or along the latter. These ports may 20 be provided with suitable valve means, as shown in Fig. 7, to prevent oil from escaping from the core during the assembly operations. They may be opened automatically or manually prior to the application of the final winding of insulating 25 material.

Fig. 6 shows the arrangement of an expansion vessel within the casing of a single conductor cable stop end or terminal. The expansion vessel may be combined in a similar manner with an 30 oil stop joint which is more or less equivalent to two oil immersed terminals or stop ends. In this figure 13 indicates a casing which is soldered to the sheath of the cable at its lower end as indicated at 25, and the upper end has an out-turned 35 flange which is united with that on the ring 26. Rising above the ring is an insulator 27 through the upper end of which projects a part 28 connected to the cable conductor. The expansion vessel takes the form illustrated in Figs. 2 and 3. 40 At one end of the vessel is a perforated metal screen 9 which protects it when the chambered interior of the insulator is evacuated preparatory to filling it with degasified oil. The cable sheath may have valved ports such as those hereinafter 45 described, or other means to permit oil from the interior of the cable to enter the chamber in the insulator. The interior of the expansion vessel may be filled with gas under super-atmospheric pressure through the nipple 10^a, the same as in 50 Figs. 2 to 4.

What I claim as new and desire to secure by Letters Patent of the United States, is,—

1. A cable comprising a conductor, insulation thereon, an enclosing metal sheath and a body 55 of insulating fluid filling the spaces within the sheath, a casing surrounding the sheath and sealed thereto to define a chamber, means establishing communication between the interior of the sheath and the chamber, and a sealed expansion vessel located within the casing and substantially filling it under an operating condition and having a unitary wall made of a rubber-like material capable of expanding and contracting but which is insoluble in the fluid filling of the 65 cable, said wall being moved by change in volume of the fluid within the cable and casing and limited in its expansive movements by the casing.

2. A cable comprising a conductor, insulation thereon, an enclosing metal sheath and a body 70 of insulating fluid filling the spaces within the sheath, said sheath having an outlet port, a casing surrounding the sheath and sealed thereto to define a chamber normally in free communication with the port, and a sealed expansion vessel 75

enveloping the sheath and located within the chamber and substantially filling it to compensate for changes in volume of the fluid in the cable, said vessel comprising a body of rubber-like material but which is insoluble in the insulating fluid yet capable of stretching and contracting with changes in the volume of the fluid within the cable and casing to compensate for such changes and prevent excessive pressures therein, the stretching of the vessel being limited by the inner wall of the casing.

3. A cable comprising a conductor, insulation thereon, an enclosing metal sheath and a body of insulating fluid filling the spaces within the sheath, said sheath having a port through which the fluid is free to flow when the cable is in service, a rigid walled casing surrounding the sheath and sealed thereto to define a chamber of fixed size, a sealed expansion vessel enveloping the sheath and located within the casing and substantially filling the chamber under an operating condition, said vessel having a non-metallic wall made of a material which is expansible and contractible, one side of which is acted upon by fluid issuing from the port, the other side being acted upon by gas under pressure, and means through which the gas is supplied.

4. A cable comprising a conductor, insulation thereon, an enclosing metal sheath having an opening therein, and a body of liquid insulation filling the spaces within the sheath not occupied by the conductor and its insulation, a casing surrounding the sheath and sealed thereto on opposite sides of the opening to define a chamber, a vessel within the chamber surrounding the sheath and sealed at its ends around the sheath, said vessel having a non-metallic expansible and contractible wall, a perforated support between the sheath and wall to limit the inward movement thereof, and means for filling the portion of chamber outside of the wall with elastic fluid.

5. A cable comprising a conductor, insulation thereon, an enclosing metal sheath having a lateral port, and a body of insulating liquid filling the spaces within the sheath, an inwardly opening valve for the port, a casing surrounding the sheath and sealed thereto to define a chamber, a sealed expansion vessel within the casing enveloping the sheath and having a non-metallic wall made of a material which is expansible and contractible and is moved by the liquid issuing from the port after the valve has been opened to compensate for changes in volume thereof, and means for imposing a superior pressure outside of the sheath to cause the valve to open.

6. A pair of hollow liquid filled cables, a connector uniting the ends of the conductors thereof, ports in the connector through which liquid from the cable flows in and out, a body of insulation surrounding the cable ends and the connector, a perforated annular support surrounding the body of insulation and supported at its ends by the sheaths, a tubular vessel surrounding the support and sealed to the sheath at its ends, said vessel having an elastic non-metallic wall, a metallic casing enclosing the vessel and sealed to the sheath and defining a chamber, and a filling of elastic fluid between the wall of the vessel and the adjacent wall of the casing.

7. A cable comprising a conductor, insulation thereon, an enclosing metal sheath and a body of insulating liquid filling the spaces within the sheath, a casing surrounding the sheath and sealed thereto at its ends and defining a chamber, means permitting egress of fluid from the

cable into the chamber, and a sealed expansion vessel located in the chamber and having a movable wall acting in opposition to the body of liquid, said vessel having a non-metallic elastic wall made of synthetic material which is impervious to said liquid, said wall being secured at its ends only around the sheath.

8. A cable comprising a metallic sheathed insulated conductor, an enclosing casing for a portion of the cable which is sealed at its ends to form a chamber, a vessel located within the chamber of the casing and having an elastic wall, the ends of which are sealed about the cable, and aligned nipples for the enclosing casing and the elastic wall by means of which different fluids may be admitted to the space inside of the elastic wall and to that between the wall and the casing.

9. A cable comprising a pair of metal sheathed insulated conductors, a connector for uniting them, insulating fluid within the sheaths, insulation applied over the connector and adjacent ends of the conductors, a metallic casing, the shape of which approximates that of the applied insulation, said casing being sealed at its ends to the sheaths, a perforated metal member enclosing the applied insulation and approximating the shape thereof, and a vessel having an expansible and contractible wall, which is located between the perforated member and the wall of the casing, said member limiting the inward movement of the wall and the casing the outward movement.

10. A cable comprising an insulated conductor, an enclosing metal sheath, a body of insulating fluid filling the spaces within the sheath, a chambered casing surrounding the cable and having tapered ends sealed to the sheath, means normally establishing free communication between the interior of the sheath and the chamber, a sealed vessel of non-metallic material located within the chamber, surrounding the sheath and extending into the tapered ends of the casing and substantially filling the casing under certain conditions of operation, the wall of said vessel being capable of stretching and contracting and in so doing to compensate for changes of volume of the fluid in the sheath and casing and being insoluble in said fluid, said casing limiting the movements of the wall in one direction, and other means for limiting its movements in the opposite direction.

11. A cable comprising a conductor, insulation thereon, an enclosing metal sheath and a body of insulating fluid filling the spaces within the sheath, a tubular casing surrounding the sheath and sealed thereto and defining an annular chamber, means permitting the fluid to flow from the sheath into the chamber, a tubular expansion vessel located inside the casing comprising a non-metallic expansible and contractible wall sealed at its ends to the sheath and defining an annular partition, the inner surface of which is acted upon by the fluid from the cable, and by its movements compensates for changes in volume of the fluid, the outward movement of the wall being limited by the inner surface of the annular casing, a support located between the cable and the wall to limit the inward movement thereof, and a body of gas under pressure acting on the outer surface of the wall in opposition to the fluid from the cable.

12. A cable comprising a conductor, insulation thereon, an enclosing metal sheath and a body of insulating liquid filling the spaces within the sheath, an annular casing surrounding the sheath and sealed thereto at its ends to define a chamber,

- means permitting liquid to flow from the cable into the chamber, and a sealed expansion vessel located within the chamber and confined in place by the inner wall of the casing and the cable and 5 acting in opposition to the body of insulating liquid as its volume increases, said vessel having a wall made of synthetic material capable of stretching and contracting and which is insoluble in the liquid acting thereon.
- 10 13. A cable installation comprising an insulated conductor, an enclosing sheath therefor, a body of insulating fluid filling the spaces within the sheath, a casing surrounding the sheath and con-

nected thereto and defining a sealed chamber, communicating means between the cable and casing for the fluid, a sealed vessel having a wall made of non-metallic material which is expandable and contractible and is located wholly within the chamber of the casing and substantially filling it when in a distended condition due to increase in volume of the fluid caused by a rise of temperature thereof, and means available from the outside of the casing through which elastic 10 fluid may be introduced into the interior of the vessel.
